(57) **CLAIM**

The ornamental design for a sanitary hand shield, as shown and described.

DESCRIPTION

FIG. 1 is a perspective view of our ornamental design for a sanitary hand shield.

FIG. 2 is another perspective view of our ornamental design for a sanitary hand shield.

FIG. 3 is an end elevation view of our design.

FIG. 4 is a bottom plan view of our design.

FIG. 5 is a top plan view of our design; and,

FIG. 6 is an end elevation view of our design. The broken lines in the drawing represent environmental structure only and form no part of the claimed design.
